UNITED STATES PATENT OFFICE

148,931

DESIGN FOR A RAZOR AND BLADE HOLDER

Horner H. Hopkins, Des Moines, Iowa, assignor
to Cobbs-Hopkins Company, Des Moines, Iowa

Application May 11, 1946, Serial No. 129,617

Term of patent 14 years

(Cl. D4—3)

To all whom it may concern:

Be it known that I, Horner H. Hopkins, a citizen of the United States, residing at Des Moines, in the county of Polk and State of Iowa, have invented a new, original, and ornamental Design for a Razor and Blade Holder, of which the following is a specification, reference being had to the accompanying drawing, forming a part thereof.

Fig. 1 is a perspective view, Fig. 2 is a front view, Fig. 3 is a side view, and Fig. 4 is a bottom view of a razor and blade holder, showing my new design.

I claim:

The ornamental design for a razor and blade holder, substantially as shown.

HORNER H. HOPKINS.
